UNITED STATES PATENT OFFICE.

LOUIS D. GREGG, OF HACKENSACK, NEW JERSEY, ASSIGNOR TO THE GREGG COMPANY, LIMITED, OF NEW YORK, N. Y., A CORPORATION OF NEW YORK.

VEHICLE FOR THE TRANSPORTATION OF SUGAR CANE AND THE LIKE.

Application filed January 10, 1925. Serial No. 1,646.

This invention relates primarily to a railway or other car of the type used for the transportation of sugar cane, although not necessarily limited to such specific purpose, and, more particularly, to the improvement of the removable or movable side closure with which such a car is usually provided on at least one of its opposite sides, or ends, for the discharge of the load.

10 By far the greater part of the sugar cane grown at the present time is transported from the plantation where it is cut to the centrale, where it is ground, in railway cars, often of narrow gauge, which for the most part are loaded and unloaded by mechanical means designed especially for the purpose.

These cars, as they have now become more or less standardized both in wood and in steel, comprise an underframe which is 20 covered by a solid or slat flooring and carries, rigidly mounted thereon, two solid or open-frame end walls and, in the case of the longer cars, intermediate thereof one or more similar transverse walls dividing the car into

25 a plurality of compartments; and, for the closure of the sides which support the cane, running from three to fifteen feet in length and usually loaded lengthwise of the car, are provided with stakes set into stake-

30 pockets attached usually to both sides of the underframe or, on one or both sides or ends, with some one of the various forms of side-discharge doors which are pivotally mounted at the top or bottom to swing outwardly about a horizontal longitudinal axis.

The cars heretofore developed, however, have all proven unsatisfactory in some respect at least. In order to carry the amount of cane required for their economical use, 40 the cars must be loaded high above the three-foot (more or less) ends and sides ordinarily provided, which can only be done when the cane is carefully piled on by expensive hand labor. Hence it is necessary, to render 45 available the mechanical derricks or other labor-saving loading devices, to make the ends and sides of the cars about twice their usual height, or say six feet. The discharge door hinged at its lower edge can then no

longer be used, since the width (or height) 50 of the door does not permit it to swing down perpendicularly or far enough to be out of the way of the falling cane. Moreover, the cane when dropped into the car by the mechanical loaders, instead of being hand laid, 55 is more or less jumbled and the increased pressure of the load due thereto is too great for the old side stakes supported only at their lower ends in the stake-pockets. These taller stakes have accordingly been braced 60 at or near their upper ends by a rigidly mounted horizontal rail. But, while cars with stakes thus supported and cars with discharge doors pivoted at the top can be unloaded by lifting the cane out from the top 65 or by tipping the cars about thirty degrees to the side, the fixed rail for bracing the stakes or to which the swinging door is hinged renders impossible the use of either 70 one of the two forms of convenient mechanical rakes which have been developed for the purpose of raking the cane from the cars.

The object of my present invention is to remedy this defect by providing a closure 75 for the discharge side or end of a car of the type in question which when locked in closed position will support the load piled against it and when released will open up the entire side of the car, or compartment, so as to leave no obstruction whatever above the 80 flooring.

To this end, the invention comprises, as its principal or essential feature, a door or pair of doors, or the two sections of a double door, each of which is hinged to the end of 85 an end wall of the car, to swing about a vertical axis; which doors may be solid or of open framework either rigidly or flexibly joined, may be of a width to meet at the center of the car when swung together or 90 may be narrower so as to leave a more or less extended central opening, and may be releasably locked in closed position at the side of the car in various ways. It also includes 95 the other novel features and combinations of elements hereinafter described and particularly pointed out in the appended claims.

Several practical embodiments of the in-

vention are shown, by way of illustration and not of limitation, in the accompanying drawings, wherein—

Figure 1 is a view showing, in side elevation, a car equipped with my new doors; Fig. 2 is a detail, in perspective, of the upper hinge on one of the doors; Fig. 3 is a view, similar to Fig. 2, illustrating a door of slightly different construction; Fig. 4 is a side elevation of the underframe and superstructure of a car showing another modification of the doors; Figs. 5 and 6 are views, in side elevation, of one-half of a car, illustrating still further modifications of its doors; and Fig. 7 is a detail, in perspective, of the upper hinge of the door shown in Fig. 6.

Referring first to Figs. 1 and 2, A indicates the underframe of the car, and B B are the steel channel corner stakes of the fixed walls, here shown as end walls, which are usually closed by a plate sheathing. The two open-frame doors D D are each formed by upper and lower frame members 1, 2 and two side frame members 3, 4, all preferably of channel section, which at the four corners are reinforced by gussets and braced by cross diagonals 5, 6, the two parts of one diagonal being joined together and to the other by plates 7. The doors are hinged to the corner stakes by means of an extension 8 of the outer corner gusset, top and bottom, which is shaped into a hinge-member and pivoted in a pivot-block 9 secured to a corner stake. The inner side channel 4 of both doors is extended downwardly at 10, and the doors are held in closed position by locking these extensions in releasing stake-pockets 11, 11, of known or of any suitable type, attached to the side of the underframe. The doors when closed and locked to the underframe are not only fixed at three of their corners but, as will be seen, at the single free corner are braced against the lateral pressure of the load by the effective cantilever action of the diagonal 6.

The door D illustrated in Fig. 3 is the same as before, except that the framework is sheathed by a steel plate 12 and the diagonal 5 is omitted as here unnecessary.

In Fig. 4 the doors D¹ D¹, framed by upper and lower and two side channels braced by corner gussets and closed by planks bolted top and bottom to the channels, are hinged to the corner stakes in the manner described. At here shown, however, they are of a width to meet, substantially, at the center of the car, and they are releasably locked together, both at the top and at the bottom, by a hasp-bar 13 which is pivoted to the frame of one and swings down behind a keeper-plate 14 attached to the frame of the other. The two hasp-bars can readily be connected by a rod, if desired, to move 65 together.

As illustrated in Fig. 5, the inner side channel of the open frame door D² is omitted and in place thereof two upright stakes or bars 15, 16 are bolted to the upper and lower channels, the stake 16 being extended downwardly below the top of the underframe to serve as a stop. The two doors are hinged to the corner stakes by gusset hinge-members, as before, and, like the doors of Fig. 4, are locked together by hasp-bars. 75

In the last modification, Figs. 6 and 7, each of the two doors D³ (only one of which is shown) is an open parallelogram framed by upper and lower channels and by two uprights or stakes 17, 18 which are pivoted thereto by bolts. The two channels of each door are hinged to a corner stake each by a hinge member 19 which is pivoted to the head of a bolt 20 swiveled between a strap 21 and the outer flange of the stake to which it is secured, thus providing a universal joint connection. These doors, which swing outwardly and downwardly when released, are locked together at the top by a hasp-bar and each is further secured to the underframe by locking the downward extension of the inner stake 18 in a releasing stake-pocket. 85

In all cases the car is provided with a discharge side which, when the doors are released, is entirely open above the flooring. 95

It will of course be understood that the doors may be further modified in the details of their construction without departing from the spirit or sacrificing the advantages of 100 my invention.

What I claim as new, and desire to secure by Letters Patent, is—

1. A vehicle of the character described which comprises an underframe and two spaced walls and which on its discharge side is provided with a door hinged to a wall to swing about a vertical axis, said discharge side having no fixed connection between the walls above the underframe. 105

2. A vehicle of the character described which comprises an underframe and two parallel walls and which on its discharge side has no fixed side member between the walls and is provided with doors hinged to the walls and with means for releasably locking the doors in closed position. 115

3. A vehicle of the character described which comprises an underframe and two end walls with corner stakes and which on one of its sides is closed only by doors framed with steel members and hinged to the corner stakes to swing outwardly about a vertical axis. 120

4. A vehicle of the character described comprising an underframe, two end walls with steel channel corner stakes, and a discharge side closure which consists of two doors framed by steel channels braced at the corners by gussets and hinged at their outer 125 130

sides to the corner stakes by hinged extensions of the upper and lower gussets and means for releasably locking the doors in closed position at the side of the underframe.

5. In a vehicle of the character described, the combination with an underframe and two spaced walls of a discharge side closure

comprising a door which is framed by members including two crossed diagonals and which is hinged at its inner side to a wall ¹⁰ to swing thereon about a vertical axis and when closed is locked at its lower outer corner.

LOUIS D. GREGG.
